UNITED STATES PATENT OFFICE.

RUSSELL E. IRISH, OF DORMONT, PENNSYLVANIA.

DENTAL MODEL TRIMMER.

Application filed May 19, 1926. Serial No. 110,304.

This invention relates to a dental model trimmer.

It is usual in orthodontia, and for other dental purposes, to make plaster representations of the teeth and adjacent oral tissues of the patient. It is necessary that these plaster models receive a planed finish in order to true them up, and secure an accurate relative positioning of the anatomic portions of the upper and lower casts. It is desirable that the capitals, that is the block portions of the casts carrying the anatomical portions, be accurately and artistically trimmed.

One object of the present invention is to provide a model trimming machine in which a suitable planing knife is reciprocated by power to make a rapid trimming of the cast.

Another object of the invention is to provide means for receiving and disposing of the shavings from such trimming action, so that they may not collect on working parts of the machine or soil the laboratory in which the work is done.

Another object of the invention is to provide means in a model trimming machine of this nature which assists in the accurate presentation of the cast to the path of movement of the cutting knife, thus insuring accurate and artistic trimming of the model.

In the accompanying drawings Figure 1 is a side elevation of the complete model trimming machine; Figure 2 is a bottom plan view of one of the members constituting the plane block of such machine; Figure 3 is a similar view of the other member of the plane block, illustrating the cutting blade of the block and the manner of its attachment therein; Figure 4 is an elevation of

the blade engaging face of the block member shown in Figure 2; Figure 5 is an elevation of the blade engaging face of the block member shown in Figure 3; Figure 6 is a fragmentary vertical section through a portion of the plane block shown in Figures 3 and 5, illustrating the attachment of a connecting rod to the plane block; Figure 7 is a similar view illustrating a modified attachment of the connecting rod to the plane

block; Figure 8 is a plan view of the work supporting platform or table upon which the dental model rests during the trimming operation; and Figure 9 is a front elevation of the platform or table shown in Figure 8.

In the drawings the reference numeral 1 designates the base of the machine, to which are attached uprights 2 supporting guide members or rails 3 and 4 for the plane block 5. Plane block 5 has therein upper and lower channels 6 and 7, which respectively engage the upper and lower guide bars 3 and 4, and serve to mount the plane block for reciprocation in the frame of the machine. Plane block 5 is caused to reciprocate by means of a connecting rod 5^a, which is pivotally attached to one end of an arm 8 having a pivoted mounting 9 in a bracket 10. For part of its length the arm 8 is divided into guide bars 8^a providing a path 11 for a sliding head 12. Sliding head 12 is connected with a crank 13 fixed on a shaft 14. The shaft 14 is rotated by means of a worm gear 15, which meshes with a worm 16 on a shaft 17 directly connected with an electric motor 18.

The plane block 5 comprises two block members 19 and 20, connecting rod 5^a being attached to the member 19 of the block. This attachment, as shown in detail in Figure 6, comprises a pin 21, which passes through an orifice in the block member and through the connecting rod 5^a, the pin having a threaded engagement in the body of the block member. The block member 19 has therein a recess 22 to receive the end of the connecting rod for its attachment by connecting pin 21.

In the modified attachment shown in Figure 7 of the drawings connecting rod 5^a is attached to the block member 19 by means of a bracket 23 secured in a recess 24 in the body of the block. This bracket comprises lugs 25 to which the connecting rod is attached by connecting pin 26.

The cutting blade 27 of the plane block is adjustably attached to the face 28 of the block member 19. For such attachment a recess or channel 29 is provided in the face of the block member, and accommodates a screw 30 carrying a traveller 31 slidably in the channel 29. Screw 30 is rotatably mounted in a bushing 32 held in position by strap 33, and is rotated by means of a winged head 34. Longitudinal movement of the screw is prevented by a shoulder 35 bearing against the bushing 32. The cutting blade 27 is adjustably mounted in the plane block by its attachment to the traveller 31.

as by means of screws passing through countersunk screw holes 36 in the cutting blade and engaging the traveller.

As the cutting blade 27 extends outwardly from the face 28 of block member 19 on a considerable portion on the area of such face, the matching face 37 of block member 20 is recessed to embrace the blade. The two block members may be mutually connected by means of bolts engaging in matching bolt holes 38 adjacent the edges of the block members.

In the thicker portion of plane block 20 is a passage 39, which extends the entire width of the cutting blade 27. This passage incidentally provides space for the issuance of the cutting blade from between the block members and avoids the necessity of a bevelled edge on the block member 20 for permitting exposure of the cutting edge of the blade. From passage 39 a plurality of short passages or ports 40 lead to the lower surface of the plane block. In use of the device shavings from the cutting blade 27 enter the passage 39, and are delivered beneath the plane block by way of the passages or ports 40. A drawer 41 is preferably provided in the base 1 of the machine to receive the shavings from the plane block. As the machine is used in shaving plaster, the shavings are finely divided, and readily flow through the passages 39 and 40 into the drawer 41.

Adjacent the face of the machine is a work supporting platform or table 42, for supporting the cast while presented to the plane block. For accurately positioning such cast on the work supporting table with respect to the path of movement to the plane block, the table 42 is provided with an adjustably mounted presser bar 43. This presser bar is mounted in arcuate slots 44 in the table by means of square headed bolts 45 and winged nuts 46. The shank of each bolt passes through one of the slots 44 and through a slot 47 extending longitudinally of the presser bar, to engage one of the nuts 46. By this mounting the presser bar may be adjusted on the work supporting table or platform 42 by movement along the arcuate slots 44. It may also be adjusted to the desired angle at which the cast is to be planed by swinging the presser bar on its attaching bolts. An exact angular adjustment is facilitated by means of parallel markings 48 on the upper surface of the platform 42 and at right angles to the plane of the cutting blade 27.

The outer face of the plane block 5 is extended longitudinally by means of a guide plate 49, which is secured by screws 50 to an inset face 51 on the block member 20. The use of this guide plate makes it possible to press the cast being planed against the face of the plane block proper and the

guide plate, during the reciprocation of the plane block, since it prevents the entire face of the plane block passing beyond the work during reciprocating movement of the plane block.

The dental model trimmer of the present invention has the great advantage of being motor driven, thus speeding up the work of trimming the casts and leaving both hands of the operator free for presenting the cast to the cutting plate of the machine. It also presents advantages over motor driven trimmers using a revolving blade. This is because the arrangement is such that the cast may be easily positioned with respect to the cutting plate to secure the desired planing effect, and because the planing away of the material of the model may be easily observed during the operation. It therefore requires less skill to use the machine than to use a model trimmer having a revolving blade, and permits the work to be more rapidly accomplished.

What I claim is:

1. In a dental model trimmer the combination of a machine frame, a plane block mounted for reciprocating movement in the frame, means for reciprocating the plane block, a work supporting table mounted in the path of movement of the plane block and having arcuate slots therein, a slotted presser bar, and fastening members passing through the slot in the presser bar and the slots in the table for fastening the presser bar in adjusted position on the table.

2. In a dental model trimmer the combination of a machine frame, a plane block mounted for reciprocating movement in the frame, means for reciprocating the plane block, a vertically disposed cutting blade in the plane block, a work supporting table mounted in a plane at right angles to the cutting blade having arcuate slots therein and having on the surface thereof a plurality of markings at right angles to the plane of the cutting blade, a slotted presser bar, and fastening members passing through the slot in the bar and the slots in the table for fastening the presser bar in adjusted position on the table.

3. A plane block comprising two portions having inclined matching faces, a cutting blade, adjustable blade holding means disposed in a recess in the face of one portion and the face of the other portion being recessed to embrace the blade, and a guide plate secured to one portion adjacent the point of issuance of the cutting blade.

4. A plane block comprising two block members having inclined matching faces, and a cutting blade; the faces of said members being arranged for the accommodation and adjustment of the blade, and one of said members being provided with intercommunicating passages for receiving shavings from

the cutting blade interiorly of the block and for discharging the shavings therefrom.

5. A plane block comprising two block members having inclined matching faces, a cutting blade, adjustable blade holding means disposed in a recess in the face of one of the members, the face of the other member being recessed to embrace the blade, and a guide plate secured to one member adjacent the point of issuance of the blade, one of said block members being provided with passages for receiving shavings from the cutting blade interiorly of the plane block and for discharging shavings therefrom.
10. 6. A plane block comprising two block members having inclined matching faces, and a cutting blade; the faces of said members being arranged for the accommodation and adjustment of the blade, and one of said members being provided with a passage extending the length of the cutting blade and with a second passage at approximately right angles thereto and providing communication from said first named passage to the under side of the plane block.

15. 7. In a dental model trimmer the combination of a machine frame, a plane block mounted for reciprocating movement in the frame, said plane block comprising two block members having inclined matching faces, a cutting blade, the faces of said members being arranged for the accommodation and adjustment of the blade; and one of said members being provided with passages for receiving shavings from the cutting blade interiorly of the block and for discharging the shavings therefrom; and a receptacle in the machine frame for receiving shavings from the plane block.
20. 8. In a dental model trimmer the combination of a machine frame, a plane block mounted for reciprocating movement in the frame, means for reciprocating the plane block, a cutting blade, said plane block comprising two block members having inclined matching faces, the faces of said members being arranged for the accommodation and
25. 9. In a dental model trimmer the combination of a machine frame, a plane block mounted for reciprocating movement in the frame, said plane block comprising two block members having inclined matching faces, a cutting blade, the faces of said members being arranged for the accommodation and adjustment of the blade, one of said members being provided with passages for receiving shavings from the blade interiorly of the plane block and for discharging shavings therefrom, a work supporting table mounted in the path of movement of the plane block and having arcuate slots therein, a slotted presser bar, and fastening members passing through the slot in the presser bar and the slots in the table for fastening the presser bar in adjusted position on the table.

30. 10. In a dental model trimmer the combination of a machine frame, a plane block mounted for reciprocating movement in the frame, means for reciprocating the plane block, a cutting blade, said plane block comprising two block members having inclined matching faces, the faces of said members being arranged for the accommodation and adjustment of the blade and one of the members being provided with a passage extending the length of the cutting blade and with communication from said passage to the under side of the plane block, a work supporting table mounted adjacent the path of movement of the plane block and having arcuate slots therein, a slotted presser plate, and fastening members passing through the slot in the presser plate and the slots in the table.

35. 11. In a dental model trimmer the combination of a machine frame, a plane block mounted for reciprocating movement in the frame, means for reciprocating the plane block, a cutting blade, said plane block comprising two block members having inclined matching faces, the faces of said members being arranged for the accommodation and adjustment of the blade and one of the members being provided with a passage extending the length of the cutting blade and with communication from said passage to the under side of the plane block, a work supporting table mounted adjacent the path of movement of the plane block and having arcuate slots therein, a slotted presser plate, and fastening members passing through the slot in the presser plate and the slots in the table.

40. In witness whereof, I hereunto set my hand.

RUSSELL E. IRISH.
